C. W. CADE

TRUCK

Filed June 2, 1920

FIG. 1

FIG. 2

INVENTOR

Charles W. Cade
By Kay, Fetter & Brown
attys

UNITED STATES PATENT OFFICE.

CHARLES W. CADE, OF BELLEVUE, PENNSYLVANIA, ASSIGNOR TO MCKINNEY MANUFACTURING COMPANY, OF PITTSBURGH, PENNSYLVANIA, A CORPORATION OF PENNSYLVANIA.

TRUCK.

Application filed June 2, 1920. Serial No. 386,083.

To all whom it may concern:

Be it known that I, CHARLES W. CADE, a citizen of the United States, and resident of Bellevue, in the county of Allegheny and 5 State of Pennsylvania, have invented a new and useful Improvement in Trucks, and I do hereby declare the following to be a full, clear, and exact description thereof.

My invention relates to a truck for handling carboys containing acid and chemicals.

The object of my invention is to provide a truck of this character adapted for transferring carboys from one point in the warehouse to the other, in which the carboy when 15 mounted thereon is held securely and firmly in position without liability of breaking the neck of the bottle extending out therefrom.

A further object of my invention is to provide a truck of this character in which 20 one man can readily mount the carboy on the truck, and one which will handle the heaviest carboy without attendant dangers which so often occur in the breakage of carboys containing injurious chemicals.

25 In the accompanying drawing, Fig. 1 is a perspective view of my improved carboy truck; Fig. 2 is a like view showing the carboy in position thereon and during transportation.

30 In the drawing, the numeral 2 designates a suitable axle on which are mounted the wheels 3 adapted to rotate loosely thereon. Wheel-guards 4 are mounted on the axle and are connected on the inside to the fork 5 at 35 the lower end of the shaft 6. This shaft 6 is connected to the axle in any suitable manner.

Secured to the fork 5 and to the axle are the toe-pieces 7 which are adapted to be 40 wedged underneath the carboy, as will more fully hereinafter appear. The arms of the fork 5, project beyond the axle 2, and the toe-pieces 7 are secured to the outer ends of said arms by the bolts 7a. This assists in 45 holding the toe-pieces securely in position, and yet permits them to project sufficiently beyond the wheels to enable the toe-pieces to be forced under the carboy.

Mounted on the shaft 6 is the foot-plate 50 or step 8 of the ordinary type.

The grappling-hook 9 has the teeth 10 which are adapted to engage the pins 11 arranged at intervals in the shaft 6.

A fork 12 is formed on the outer end of 55 the grappling-hook 9, said fork having the

downwardly extending hook-portions 13. At the outer end of the shaft 6 is the handle 14.

When my improved truck is in use and it is desired to lift the carboy 15, the operator 60 grasps the handle 14 and, by bringing the shaft 6 to substantially a vertical position, the toe-pieces 7 are brought into contact with the floor. The grappling-hook is adjusted with its hooks engaging the front of 65 the carboy and by placing his foot upon the foot-plate 8, the operator tilts the carboy and in so doing he is able to wedge the toe-pieces under the bottom of the carboy. The fork 12 of the grappling-hook surrounds 70 the neck 17 of the bottle and the hook-portions 13 hook over the outer face of the box and engage the said box at opposite sides of its mid-line, so that there is no danger of the carboy wobbling from one side to the 75 other or slipping from the truck. In this position the carboy is securely held in position on the truck and may be wheeled to any point in the warehouse without danger of working loose, and as the fork 12 surrounds 80 the neck, there is no danger of the neck being broken.

Furthermore, the mounting of the carboy on the truck may be safely and readily performed by one man without the least difficulty.

In chemical works, wholesale drug houses, and all industries where carboys must be transported either in protecting crates or in original form, my improved truck will 90 handle the heaviest carboys without danger of breakage, which in the handling of injurious chemicals may result in very serious injury to the workmen.

What I claim is:

In a truck for handling carboys, the combination of an axle, wheels mounted thereon, a shaft connected to said axle, fork-arms connected to said shaft, toe-pieces connected to said axle, and to the projecting ends of said fork-arms, and a forked grappling hook mounted on said shaft, adapted to enclose the neck of the bottle, and engage the front face of the carboy.

In testimony whereof, I the said CHARLES 105 W. CADE, have hereunto set my hand.

CHARLES W. CADE.

Witnesses:

ROBERT D. TOTTEN,
JOHN F. WILL.
